CLAIM

The ornamental design for a footrest, as shown and described.

DESCRIPTION

FIG. 1 is a perspective view of a footrest, showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown on the bottom of the footrest are for the purpose of illustrating portions of the footrest that form no part of the claimed design.
